SAFE DIAPER CLASP

Clyde M. Hamblin, Washington, D. C.

Application May 29, 1950, Serial No. 165,069

5 Claims. (Cl. 24—161)

1

This invention relates to a safe diaper clasp and has for an object to provide an improved substitute for the safety pin as used on baby diapers and eliminate the danger resulting when a baby swallows an open safety pin.

A further object of this invention is to provide a clasp substituting for a conventional safety pin in fastening a diaper about a baby which clasp is so shaped that it will secure the diaper in position just as firmly as a conventional safety pin which will lie flat against the body of the baby when in position, and which, if accidentally swallowed by the baby, will pass safely through the baby's system without danger of injuring the baby's stomach or intestines and without danger of lodging anywhere within the baby's body but which will be discharged from the baby's system in a natural manner.

A further object of this invention is to provide a safe diaper clasp which is as inexpensive to manufacture as the conventional safety pin but which is incapable of causing injury if accidentally swallowed or otherwise taken into the human body because it is entirely free of any externally projecting sharp edges and instead it is provided with rounded external surfaces whereby it cannot cause any cuts, tears, or other injuries as it passes through and out of the human body.

Many children have been endangered by swallowing open safety pins, necessitating dangerous operations in order to remove such open safety pin from the human body. Bronchoscope operations are usually necessary in removing an open safety pin from the human body but as the number of doctors skilled in such operations is extremely small, the time necessary in bringing the patient to the doctor, often from a distant city, sometimes proves fatal to the patient. Open safety pins are an ever present danger in a baby's life. It is an object of this invention to provide a clasp for fastening diapers in position on a baby which clasp if accidentally swallowed cannot cause any internal injury to the baby but which should pass safely through the baby's system and be discharged therefrom without injury.

A further object of this invention is to provide a safe diaper clasp which may be made of metal by a simple stamping and bending operation so that the clasp may be manufactured and sold at a low cost easily competitive with the cost of the safety pin.

A further object of this invention is to provide a safety diaper clasp made of a single piece of sheet material suitably stamped, pressed and folded into final form and provided with a plu-

2

rality of diaper cloth engaging projections which projections are so inclosed within a clasp body that they are incapable of causing any injury within the human body should the completed clasp be accidentally swallowed.

A further object of this invention is to provide a safety diaper clasp having a flattened body and rounded edges together with internally located diaper cloth engaging and penetrating projections, which projections are so located and spaced from the rounded edges of the clasp that they are incapable of accidentally causing injury to the human body either internally or externally.

A further object of this invention is to provide a safe diaper clasp which will eliminate every mother's ever-present fear that she may prick the baby with the pin of a safety pin while diapering the baby as well as the fear that the baby may accidentally swallow an open safety pin with the resultant and possibly fatal danger.

With the foregoing and other objects in view, this invention comprises the combination, constructions and arrangement of parts hereinafter set forth, claimed, and disclosed in the accompanying drawing wherein:

Fig. 1 shows a blank from which one form of the clasp of this invention is made.

Fig. 2 is a plan view of the blank of Fig. 1 after it has been cupped and the projections have been bent.

Fig. 3 is an edge view of Fig. 2.

Fig. 4 is a sectional view on the line 4—4 of Fig. 2.

Fig. 5 is an edge view of a completed clasp.

Fig. 6 is a sectional view through a completed clasp.

Fig. 7 is a blank for making a slightly modified form with the projections extending from the end instead of the sides.

Fig. 8 is a plan view of the blank of Fig. 7 after the cupping and bending operation of the projections has been completed.

Fig. 9 is a sectional view on line 9—9 of Fig. 8.

Fig. 10 is an edge view of a completed clasp of this form.

Fig. 11 is a plan view of still another form with a blank already cupped and the projections struck in within the perimeter thereof.

Fig. 12 is a sectional view on line 12—12 of Fig. 11 and

Fig. 13 is an edge view of the completed clasp of this form.

There is shown at 10 a blank from which one form of this invention is made. This blank 10 is shaped roughly like a figure 8 with a project-

ing finger 11 extending from each side corner thereof. The blank 10 consists of an upper lobe 12 and a lower lobe 13 connected together by a slightly narrowed hinge forming portion 14. In making the blank 10 into the finished safe diaper clasp shown at 15 the blank 10 is first cupped so as to have sides 16 extending completely therearound, the edge 17 of the cupped side 16 being preferably at a tangent to a right angle extending from the plane of the lobes of the blank 10 at the same time the fingers 11 are bent inwardly at 18 so as to extend parallel to the body of the lobe and then their points 20 are bent upwardly at right angles to the plane of the lobes.

The fingers 11 of one lobe are very slightly longer than the fingers 11 of the other lobe, as a result of which the points 21 of one lobe are in a slightly different plane than the points 20 of the other lobe. Next the lobes 12 and 13 are folded toward each other about the joining line 14 between the lobes thus providing the finished clasp shown at 15 with the points 20 and 21 preferably overlapping each other, although they may be in point to point contact if the fingers on both lobes are of the same length. The joining line 14 thus provides a hinge joint between the cupped lobes 12 and 13 and the points 20 and 21 are displaced from the cupped side 16 and edges 17 a substantial distance therewithin.

The metal from which the blank is formed is such that after it has been shaped to the final form shown as 15 it will be sufficiently resilient so that the lobes may be separated by means of one's fingers about the hinge joint 14 a sufficient distance to enable several layers of diaper cloth to be inserted therebetween so that when the lobes 13 are released and pressed together by one's fingers, the points 20 and 21 will penetrate the several layers of diaper cloth and thus hold the layers of diaper cloth in overlapped position just as the ordinary safety pin does. The spring of the clasp is intended to be sufficiently strong to close the clasp when no cloth extends between the lobes thereof. However, when diaper cloth is inserted between the lobes of the clasp, the pressure of one's fingers may be necessary to aid the spring and cause the points to penetrate the cloth in the same conventional manner as it is necessary to apply force to cause point of a safety pin to penetrate the diaper cloth. The completed clasp 15 is substantially flat and when placed in position on a diaper about a baby's body it will lie flat against the body of the baby and not cause any appreciable lump with resultant discomfort. While this is the preferred type of metal, obviously the metal may be stiff without resilience so that it will remain in a position to which it is bent in which case it may be opened slightly with one's fingers so that it may be placed over the layers of diaper cloth and then pressed together to hold the layers of cloth in overlapped position. In either case, however, the clasping points 20 and 21 are located entirely within and spaced from the edges of the clasp and only a rounded outer surface of the clasp can be touched. Obviously as thus constructed, there are no sharp edges or projecting points and the handling of the clasp cannot cause any injury whatsoever. Should the clasp be accidentally swallowed by a baby or child, there are no edges or points to injure or tear the stomach or intestines of the baby or child and nothing to cause it to anchor or lodge anywhere within the child's body. Instead, it will merely pass thru the stomach

and intestines and be discharged in a natural manner without the necessity of a bronchoscope or other dangerous operation to remove it from inside the child's body.

The form shown in Figs. 7 to 10 inclusive differs from the form just described only in having the fingers 25 and 26 extend from the ends of the lobes 27 and 28 rather than from the sides as in the first form. Otherwise the clasp 30 is formed and used in the same manner as the clasp 15 with its points 31 and 32 overlapping each other as shown. In this form the plane of the points 31 and 32 is shown as parallel to the plane of the hinge joint 33 whereas in the first form the plane of the points 20 and 21 is at right angle to the plane of the hinge joint 14.

In Figs. 11, 12, and 13, the completed clasp 35 does not have any projecting fingers. Instead, clasp points 36 and 37 are struck in within the lobes 38 and 40, being shown as extending in the plane parallel to the plane of the hinge joint 41 between the lobes 38 and 40. Just as in the other forms, the points 36 and 37 are slightly displaced with relation to each other so that they overlap and penetrate through the cloth in side by side relationship to hold the cloth therebetween. The slight irregularity left in the lobe surfaces resulting from striking in the points is not sufficient to cause any danger to anyone handling or accidentally swallowing the clasp thus formed.

It will be apparent that in each form the clasp is substantially streamlined and able to pass through the human body without causing injury. Furthermore, it is likewise not liable to cause injury to any part of the outside of the body that it may come in contact with either during handling or when in operative position on a baby's diaper.

While the clasp has been shown and the structure thereof described in detail, it is obvious that this invention is not to be considered limited to the exact forms disclosed, and that changes may be made therein within the scope of what is claimed without departing from the spirit of the invention.

Having thus set forth and disclosed the nature of this invention, what is claimed is:

1. A safe diaper clasp comprising a pair of cupped lobes resiliently and integrally hinged together and diaper cloth engaging clasp points spaced inwardly from the lobe edges and extending inwardly in overlapping side by side relation so as to penetrate and hold any cloth inserted therebetween, the outside surface of the lobes and hinge joint being rounded and free of sharp points or edges liable to cause injury.

2. A safe diaper clasp comprising a pair of cupped lobes resiliently and integrally hinged together and diaper cloth engaging clasp points spaced inwardly from the lobe edges and extending inwardly in overlapping side by side relation so as to penetrate and hold any cloth inserted therebetween, the outside surface of the lobes and hinge joint being rounded and free of sharp points or edges liable to cause injury, said clasp points comprising sharpened fingers struck inwardly from the body of each lobe a distance inwardly of the cupped edges thereof and in overlapping opposed relationship.

3. A streamlined safe diaper clasp comprising a pair of cupped lobes resiliently and integrally hinged together with their cupped edges in opposing relationship and diaper material penetrating points projecting inwardly in opposed overlap-

ping relationship from said lobes a distance inwardly from the cupped edges thereof, said points being struck inwardly from each lobe body.

4. A safe diaper clasp comprising a pair of cupped lobes resiliently and integrally hinged together and diaper cloth engaging clasp points spaced inwardly from the lobe edges and extending inwardly in overlapping side by side relation so as to penetrate and hold any diaper cloth inserted therebetween, the outside surface of the lobes and hinge joint being rounded and free of sharp points or edges liable to cause injury, said clasp points comprising fingers extending inwardly from the edges of the cupped lobes parallel to the plane of the body of the lobe and then at right angles thereto in overlapping opposed relationship.

5. A streamlined safe diaper clasp comprising a pair of cupped lobes resiliently and integrally 20

hinged together with their edges in opposing relationship and diaper material penetrating points projecting inwardly in opposed relationship from said lobes a distance inwardly from the edges thereof, said points being struck inwardly from each lobe body.
